Case, Keeney, & Gage, Atcs of Wm L.
Sanderson, Troy, N.Y. —
Letters Patent No. 230. Dated August 21, 1849.

The Schedule referred to in these Letters Patent and making part of the same.

To all whom it may concern:

Be it known, that
I, Wm L. Sanderson, of Troy, in the County of Rensselaer,
and State of New York, have invented or produced a new
design of Parlor Stove Pattern which I call the Waverly
Air Tight; and I do hereby declare that the following is a

full and exact description of the same, reference being had to the accompanying drawing marked No 1, making a part of this specification.

The drawing represents a perspective view of the Stove the back plate and end, which are not seen being respectively the same as the Front plate and end represented with the exception of a Pipe hole in the back plate and a door in the end.

The design of ornament is made up of scrolls and a Vase of Flowers and Leaves on the Front plate as represented, saving thus described and ~~represented~~ my new design of Parlor Stove.

What I claim as new and desire to secure by Letters Patent is the design and configuration of an ornamental Parlor Stove, as set forth.
